United States Patent Office

Des. 193,771
Patented Oct. 9, 1962

193,771

ARMORED PATROL CAR

Russell E. Bauer, Grosse Pointe Shores, Mich., assignor to Cadillac Gage Company, Roseville, Mich.

Filed Aug. 14, 1961, Ser. No. 66,348

Term of patent 14 years

(Cl. D14—3)

FIG. 1

FIG. 2

FIG. 1 is a perspective view of an armored patrol car, showing my new design;

FIG. 2 is a top plan view;

FIG. 3 is a side elevational view;

FIG. 4 is a front elevational view; and

FIG. 5 is a rear elevational view thereof.

The side not shown is a mirror image of the side shown.

I claim:

The ornamental design for an armored patrol car, as shown and described.
